E. E. GREVE.

CASING ELEVATOR.

APPLICATION FILED SEPT. 10, 1914.

1,180,031.

Patented Apr. 18, 1916.

UNITED STATES PATENT OFFICE.

EDGAR E. GREVE, OF PITTSBURGH, PENNSYLVANIA, ASSIGNOR TO OIL WELL SUPPLY COMPANY, OF PITTSBURGH, PENNSYLVANIA, A CORPORATION OF PENNSYLVANIA.

CASING-ELEVATOR.

1,180,031.

Specification of Letters Patent.

Patented Apr. 18, 1916.

Application filed September 10, 1914. Serial No. 861,075.

To all whom it may concern:

Be it known that I, EDGAR E. GREVE, a citizen of the United States, residing at Pittsburgh, in the county of Allegheny and State of Pennsylvania, have invented certain new and useful Improvements in Casing-Elevators; and I do hereby declare the following to be a full, clear, and exact description of the invention, such as will enable others skilled in the art to which it appertains to make and use the same.

My invention relates to the construction of that class of devices commonly termed casing elevators, which are used in handling tubing and casing in boring oil or Artesian wells.

The most common form of this class of devices is that wherein the elevator is comprised of two similar parts having hinged connection, and provided with two bails for engagement with the hook of the hoist, one of which bails usually encompasses and holds the parts in fixed relation. This class of casing elevators is objectionable in that, in order to apply the elevator to the casing to be handled, it becomes necessary to detach the bails from the elevator-hook of the hoist, which necessitates the manipulating of the elevator without the aid of the hoist and adds to the labor and difficulties of the operator. To overcome these objections there have been devised what are commonly termed single bail, gate elevators, that is to say, elevators wherein a single bail only is used, the bail being pivoted on one member of the elevator to which member the other or movable member or gate of the elevator is also pivoted, and a lock is provided to maintain the proper relation of the elevator members when the elevator is loaded. In utilizing this latter class of casing elevators, the bail does not have to be removed from the hoist hook, and consequently in manipulating the elevator and introducing the casing thereinto the operator is largely relieved of the weight of the elevator, and his application of the elevator to the casing is greatly facilitated.

It is to the improvement of this latter class of casing elevators that my present invention is especially directed, and it has for its objects, first, the provision of an ample opening in the elevator to facilitate the application of the elevator to and its removal from the casing, second, such an arrange-

ment of the closure of said opening as will minimize the load on the closure when the elevator is loaded, third, such a provision and arrangement of the lock for the closure as will uniformly distribute the stresses on the closure and lock when the elevator is loaded and is operated to lift the casing, and, fourth, the provision of means on the elevator for insuring the stability of the elevator when resting on a support other than the hoist, or when detached from the elevator hook.

To this end my invention, generally stated, involves a single bail elevator having a plurality of interlocking gates or doors, the body member of the elevator on which the bail is pivoted being provided with trunnions so located that the center line of the trunnions corresponds with the center line of the elevator so that the elevator will tend to maintain the vertical position when the gates are closed, but will assume an angle to the line of the bail when the gates are open, whereby the introduction of the casing is facilitated and in hoisting, the load on the gates or doors is minimized.

A second feature of my invention involves the combination with a single bail plural gate elevator, of a latch coacting with the bail and elevator to maintain the normal relation of bail and elevator during the hoisting operation.

A third feature of my invention involves the combination with a single bail, plural gate elevator, of a plurality of vertically and oppositely operating locks or latches for securing the gates whereby the stresses on the locks are uniformly distributed.

There are other minor features of invention involving particular combinations of elements, and particular features of elemental construction, all as will hereinafter more fully appear.

In the drawings chosen for the purpose of illustrating my invention, the scope whereof is pointed out in the claims, Figure 1 is a view in front elevation of an elevator embodying my invention, parts of the bail being broken out. Fig. 2 is a top or plan view of an elevator embodying my invention in closed or operative position, the bail being shown in section, and the gates or doors in their open or inoperative position being shown in dotted lines. Fig. 3 is a view partly in section, on the line 3-3 Fig. 2

and partly in side elevation of the elevator shown in Figs. 1 and 2, and Fig. 4 is a detail horizontal sectional view taken in the plane of the line 4—4, Fig. 1.

5 Like symbols refer to like parts wherever they occur.

I will now proceed to describe my invention more fully so that others skilled in the art to which it appertains may apply the 10 same.

In the drawings, 1 indicates the body member of the elevator with which the gates or doors and bail are pivotally connected, and for this purpose the body member, 15 which is of general U-shape, comprising somewhat more than a semicircle, is provided at diametrically opposite points with trunnions 2, 2, integral therewith, the center line of the trunnions preferably coinciding 20 with the center line of the elevator so that when the gates or doors are closed in the hoisting operation the bail will tend to maintain a vertical or normal relation to the elevator.

25 The extremities of the U-shaped body member 1 are provided with knuckles 1^a, 1^b, or are pierced for the passage of the pivot bolts 3, 3 which connect the gates or doors with the elevator body 1, and the body member 1 of the elevator, at one side, in line with, and above the trunnions 2, is provided with a boss 4 having a central opening which constitutes a keeper for the reception of a latch or spring bolt carried by the bail. The 30 body member of the elevator, below and in line with the trunnions 2, 2 is provided with lugs 5 integral therewith which insure a firm base for the elevator and enable it to securely support its load when detached 35 from the hoist hook.

The numerals 6 and 7 indicate the gates or doors of the elevator which are pivoted to the body member 1 of the elevator by the pivot bolts 3, 3. These gates, which are two 40 in number, and which substantially complete the annular shape of the elevator, are of interlocking form, that is to say they interlock with each other by means of the rectangular recess 6^a of the gate 6 and the rectangular tongue 7^a of the gate 7, and with the body member 1 of the elevator by means 45 of the rectangular recesses 6^b and 7^b which receive the knuckles 1^a and 1^b of the body member 1, and said construction insures an 50 effective support of the gates from the body member 1 of the elevator. The gate 7 carries the double lock for the gates and the handle by means of which both bolts are retracted, which handle also serves as a means 55 for opening and closing the door or gate 7 which carries the bolts.

The numerals 8 and 9 indicate the locking bolts for the gates, which bolts are vertically disposed in bolt chambers located in the 60 tongue portion 7^a of gate 7, the bolt keepers

being located in the walls of the rectangular recess 6^a of gate 6. The bolt 8 is a short spring-actuated bolt which is introduced into its bolt chamber from below and secured therein, together with the spring, by an annular or perforated screw bushing or screw plug 8^a, the opening in which permits the escape of sediment or similar material which might interfere with the operation of the lock, while the longer bolt 9, which is introduced into its bolt chamber from above, is provided with a head 9^a that rests in a countersunk seat therefor so that when the elevator is loaded the collar on the casing will rest on said head 9^a and prevent any unlocking movement of the locks 8 and 9.

In order to accomodate a cross bar 10, provided with a handle bar 11 by means of which both bolts 8 and 9 may be simultaneously and reversely operated, a segmental 85 portion of tongue 7^a is cut away as at 7^b thus exposing both bolt chambers, and corresponding segmental portions of the bolts 8 and 9 are also removed, as at 8^b, 9^b, to permit the entrance of the cross bar which 90 engages and operates the bolts.

The numeral 10 indicates the cross bar which operates the bolts, said cross bar having a pivotal fulcrum 10^a on the tongue 7, and being provided with a handle bar 11. 95 The gate or door 6 may also be provided with a handle 12 by which said gate can be opened and closed.

The numeral 13 indicates a bail having suitable bail eyes 13^a by means of which it is pivoted on the trunnions 2, 2 of elevator body member 1, and 14, 14 indicate circular plates or disks secured to the ends of trunnions 2, 2 by bolts 14^a, or in other suitable manner, which disks confine the bail to the 105 pintles and prevent any springing of the bail which might cause its disengagement from the trunnions. The disks 14 are recessed or notched as at 14^b and coat with the lugs or stops 15 on the side of the bail 110 13 to limit the possible movement of the bail relative to the elevator.

16 indicates a spring bolt or latch extending through the bail 13 adjacent to trunnion 2, and which at its inner end enters a keeper in the boss 4 of the elevator body member 1, to maintain the normal relation of the bail and elevator when the elevator is loaded with the casing. The bolt 16 and spring by means of which it is actuated are confined by an annular screw plug or screw bushing 17, and the bolt is provided with a ring 18 by means of which it may be retracted when it is desired to permit the bail to assume an angular position with relation to the elevator.

The construction of the elevator being substantially such as hereinbefore pointed out, its application to the casing to be handled thereby will be as follows: Without 130

- removing the bail 13 from the elevator hook of the hoist, the elevator gates or doors 6 and 7, if locked, are first opened to the positions indicated in dotted lines in Fig. 2 of 5 the drawing by rotating the handle bar 11 and cross bar 10, which cross bar acting on the opposite locks 8 and 9 by its opposite ends will withdraw the bolts in reverse directions, whereupon the gates may be 10 opened in opposite directions to insure ample room for the entrance or exit of the casing. Next the spring bolt 16 of the bail 13 is withdrawn, whereupon, being overbalanced in one direction by the open gates, 15 the elevator will assume an angle to the bail the degree of which is controlled by the notch 14^a of disk 14 and the lug or stops 15, and the elevator, which is now in condition to receive the casing, may be swung over 20 into position on the casing by one hand of the operator, while the operator with his other hand closes the gates 6 and 7 which are automatically locked by the spring action of lock 8, the movement of lock 8 being 25 communicated to lock 9 through the medium of the intermediate pivoted cross bar 10. In the subsequent handling of the casing by the elevator, or when the bail has assumed its normal position with relation to 30 the elevator, the spring latch 16 on bail 13 will enter the keeper in boss 4 of elevator body member 1, and thereafter maintain such relation of elevator and bail as will minimize the load on the gates and uniformly 35 distribute the stresses on the locks.
- Having thus described my invention, what I claim and desire to secure by Letters Patent is:
1. In a casing elevator, the combination of 40 a body member, a plurality of closure gates therefor, a single bail pivoted on the body member of the elevator, and a lock for the closure gates.
  2. In a casing elevator, the combination of 45 a body member, a plurality of interlocking closure gates therefor, a single bail pivoted on the body member of the elevator, and a lock for the closure gates.
  3. In a casing elevator, the combination of 50 a body member having trunnions the center lines of which coincide with the center line of the elevator, a single bail pivoted thereon, a plurality of closure gates for the body member of the elevator, and a lock for the closure gates.
  4. In a casing elevator, the combination of 55 a body member having trunnions the center lines of which coincide with the center line of the elevator, a plurality of interlocking closure gates for the body member of the elevator, a single bail pivoted on the body member of the elevator, and a lock for the interlocking closure gates.
  5. In a casing elevator, the combination of 60 a body member, a plurality of interlocking closure gates therefor, and a lock for the interlocking closure gates.
  6. In a casing elevator, the combination of 65 a body member, a plurality of interlocking closure gates therefor, a plurality of locks for the interlocking closure gates, and means for simultaneously retracting the locks of the gates. 70
  7. In a casing elevator, the combination of a body member, a plurality of closure gates 75 therefor, a plurality of locks for the closure gates, and means for automatically and simultaneously actuating said locks.
  8. In a casing elevator, the combination of a body member, a plurality of interlocking closure gates therefor, a plurality of locks mounted on one of the closure gates, and means interposed between said locks whereby said locks may be simultaneously operated. 80
  9. In a casing elevator, the combination of a body member, a plurality of closure gates therefor, a plurality of locks for the closure gates, an actuating spring for one of said locks, and means interposed between said locks for actuating one lock from the other. 85
  10. In a casing elevator, the combination of a body member, a plurality of closure gates therefor, a plurality of locks for the closure gates, and an intermediate pivoted lever for simultaneously actuating said locks. 90
  11. In a casing elevator, the combination of a body member, a plurality of closure gates therefor, a plurality of locks for the closure gates, a spring for actuating one of said locks, and a pivoted lever intermediate of said locks for simultaneously operating said locks. 95
  12. In a casing elevator, the combination of a body member, a plurality of interlocking closure gates therefor, and a plurality of oppositely operative locks for the closure gates. 100
  13. In a casing elevator, the combination of a body member, a plurality of closure gates therefor, and a plurality of vertically movable oppositely operative locks for the closure gates. 105
  14. In a casing elevator, the combination of a body member having bail trunnions, a closure gate, a bail pivoted on the trunnions of the body member, recessed disks on the trunnions of the body member, and stops on the bail which limit the relative movement of the bail and elevator. 110
  15. In a casing elevator, a body member having trunnions, a closure for the body member, a bail pivoted on the trunnions of the body member, and means interposed between the body member of the elevator and the bail for maintaining the normal relation of the bail and the elevator. 115
  16. In a casing elevator, the combination of a body member having trunnions and a 120
  17. In a casing elevator, the combination of a body member having trunnions and a 125
  18. In a casing elevator, the combination of a body member having trunnions and a 130

latch keeper above and in line with one of said trunnions, a bail therefor, and a spring-actuated latch for maintaining the normal relation of the bail and the elevator.

- 5 17. In a casing elevator, the combination of a body member having trunnions the center lines of which coincide with the center line of the elevator and a keeper boss adjacent to one of said trunnions, closure gates
10 for the body member, a bail pivoted on the trunnions of the body member, and a spring latch mounted on the bail adjacent to the keeper boss of the body member and for coaction with said keeper boss.
- 15 18. In a casing elevator, the combination

of a rigid substantially semi-circular or U-shaped body member, means for suspending the body member, said suspension means and body member being capable of a relative pivotal movement when the elevator is suspended, a plurality of closure members mounted on the body member and adapted to form therewith a collar for encircling a casing, and means for locking the closure members.

In testimony whereof I affix my signature, 25
in the presence of two subscribing witnesses.
